(57) **CLAIM**

The ornamental design for a handheld medical test device with a removable cap, as shown and described.

DESCRIPTION

FIG. 1 is a top plan view of a handheld medical test device showing the design;

FIG. 2 is a bottom plan view thereof;

FIG. 3 is a left side elevation view thereof, the right side being a mirror image thereof;

FIG. 4 is a front elevation view of the design;

FIG. 5 is a rear elevation view thereof;

FIG. 6 is a perspective view of the top and left side thereof; and,

FIG. 7 is another perspective view of the device with its cap removed.
